VENETIAN BLIND

Henry J. Schultz, Hayward, Calif., assignor to
Brooks Walker, San Francisco, Calif.

Filed Mar. 11, 1957, Ser. No. 645,243

5 Claims. (Cl. 160—168)

This invention pertains to improvements in Venetian blinds and particularly to the simplified hardware at the tilt rod or top of the blinds. Another feature shows a way in which the conventional tilt rod or head rail can be dispensed with by the use of simplified hanging brackets formed of wire or suitable material and adapted for inside or outside hung blinds. Another feature is a simplified lift cord turn and tape tilt device, wherein one simple device formed of wire rides on the tilt rod and retains the ladder tape and acts on a lift cord turn. This item is formed without waste of material and requires no moving parts and will serve for the right or left hand ladder tape guide. Another feature shows a simplified way in which the lift cord retainer is formed of wire in a manner to retain the tilt cord in effective relation to the tilt rod to act directly or through a sleeve over the tilt rod to effect tilting of the ladder tape rungs and slats supported thereon without gears, pulleys, etc. Another feature is the construction of these ladder tape cord turn devices so that they may be snapped onto the tilt rod before or after the looped top of the ladder tape is assembled over the tilt rod for easy assembly. Another feature is a way in which a cord lock can be attached to the tilt rod and can locate the ladder tape guide and absorb the pull of the lift cords toward the cord lock to prevent end drift of the tilt rod toward the cord lock during lifting or other operations of the blind.

Other features will be more particularly pointed out in the accompanying specification and claims.

I have illustrated my invention by way of example in the accompanying drawings in which:

Fig. 1 shows a side perspective view of a Venetian blind incorporating one form of the invention.

Fig. 2 is an enlarged side view partly cut away of the upper left hand portion of Fig. 1 showing another tilt cord retainer and the left hand ladder tape retainer of Fig. 1.

Fig. 3 is similar to Fig. 2 but showing a bottom view.

Fig. 4 is a section at Section 4—4 of Fig. 2.

Fig. 5 is a section at Section 5—5 of Fig. 2.

Fig. 6 is a perspective view of a ladder tape retainer and lift cord turn somewhat enlarged as shown in Fig. 1.

Fig. 7 is an enlarged side elevation view of the cord lock and support shown in Fig. 1.

Fig. 8 is an enlarged view taken at Section 8—8 of Fig. 1.

Fig. 9 is a perspective view of the cord lock support as shown in Fig. 7.

Fig. 10 is similar to Fig. 8 but showing the support bracket attached to the frame from above rather than from the right as shown in Fig. 8.

Fig. 11 shows an alternate construction of the ladder tape locator and cord turn and is similar to the view shown in Fig. 5.

Fig. 12 shows a perspective view of one of the tilt rod support brackets as shown in Figs. 1, 7, 8, and 10.

Fig. 13 shows a bottom view of the construction shown in Fig. 11 without cord and tapes.

2

In all figures like numerals refer to corresponding parts.

In Figs. 1, 2, 3, 4, 5, 6, 7, 8, 9, 10, and 12 I have shown a Venetian blind with slats 5, ladder tapes 10 and 11, tilt cords 6 and 6a with cord stops 6b, bottom rail 4, support brackets 30, turn and ladder tape guides and cord turn 50 (the same part serves both purposes). Lift cords 8 and 8a pass through cord lock 70 supported on tilt rod 20 which is supported on support bracket 30. The operation of this cord lock is more particularly described in my co-pending application, Ser. No. 546,420, entitled Venetian Blind, and which application resulted in Patent No. 2,842,196 on July 8, 1958.

Tilt rod support brackets 30 are preferably formed of wire to avoid waste and have an in-turned loop end 30a that fits and supports tilt rod 20. The two ends 30b and 30c which form a right angle and are adapted for support by two screws such as 31 from the side for outside hung, as in Figs. 1, 7, and 8, or from two screws 32 from above for inside hung, as in Fig. 10. Tilt cord retainer 50 has curled ends or hooks 50b and 50c adapted to snap over tilt rod 20 after tilt cords 6 and 6a have been wound around tilt rod 20. The spacing of the hooks 50b and 50c is such that more than one complete rotation of the tilt rod is permitted, and the cord turns may travel axially of the tilt rod a distance greater than the diameter of the cord. An alternate design of tilt cord retainer 50 is shown in Figs. 2 and 3. Separating bar 40a connects the two rod engaging ends 40b and 40c, and acts as guides for the tilt cords 6 and 6a. Tilt cords 6 and 6a are wound around tilt rod 20 to allow more than one turn of rod 20 by tilt ends 6 and 6a. The tilt cord guide may either have a loop in the center portion under the tilt rod as at 50a or a straight section as 40a. If a loop is used it serves as a cord turn if under a ladder tape, as in Fig. 1, and the same bracket can then act as a tilt cord guide, as in Fig. 1, with the loop performing no extra function when used as a tilt cord guide.

The lift cords 8 and 8a pass through cord lock 70 and over support hook 60b of support 60 to cord turns 50a under ladder tapes 10 and 11. The looped upper ends of ladder tapes 10 and 11 rest on bushings 21 which are secured to tilt rod 20 and have increased friction for driving the tilt of ladder tape sides 10 and 11 as compared to the smoother surface of tilt rod 20. These bushings 21 may have washers 22 to reduce friction on the end thrust between cord turns 50 and the bushings 21 due to the pull of the lift cords, etc. A bushing similar to 21 may be used under tilt cords 6 and 6a by increasing the length of hook ends 50b and 50c to get better travel of cords 6 and 6a in effecting a full tilt of the blind. If the flat angle of the cord turn loop 50a forms too much friction a loop such as 45a of tilt cord or ladder tape locator 45 shown in Figs. 11 and 13 may be used. This loop 45a could also be used to support the cord 8 on its way to the left hand cord turn as shown in Fig. 1.

Cord lock support bracket 60 is formed so that loop 60a goes to the right of right hand support bracket 30. Hump 60c rides against the left of right hand support bracket 30 and loop 60d against the left side of cord turn bracket 50 as shown at the right side of Fig. 1. As stated previously the operation of the cord lock is described in my co-pending application, Ser. No. 546,420, entitled Venetian Blind, now Patent No. 2,842,196 above referred to and will not be described here.

With this construction the tilt cord can be assembled at the right or left of the blind as can the lift cord lock with no change in the parts required. The cord lock prevents the tilt rod from becoming disengaged with support bracket 30 unless support 60 is rotated well back for manual disengagement. The cord turns 50 and 40 work

equally well whether the cord lock is at the right or left side of the blind. This versatility forms another feature of this construction and invention.

Other features of the invention will be more particularly pointed out in the accompanying specification and claims.

To those skilled in the art to which this invention relates, many changes in construction and widely differing embodiments and applications of the invention will suggest themselves without departing from the spirit and scope of the invention.

The disclosures and the description herein are purely illustrative and are not intended to be in any sense limiting.

I claim as my invention:

1. In a Venetian blind, a pair of brackets, a tilt rod having its opposite ends rotatably supported in said brackets, tilt cords disposed adjacent one end of said tilt rod and making a plurality of turns about same, a plurality of slats disposed beneath said tilt rod, ladder tapes supporting said slats and extending over said tilt rod, lift cords operatively engaged with said slats between said tapes, a tilt cord positioning and retaining means removably engaged with said tilt rod, positioning and retaining means for each of said ladder tapes removably engaged with said tilt rod, and said brackets, tilt cord and tape positioning and retaining means each comprising a formed single length of wire.

2. The structure according to claim 1, wherein said brackets, each comprise a pair of legs having a tilt rod receiving loop intermediate the ends thereof, said legs

being spaced for reception of retaining screws therebetween and the said legs including portions disposed in right angular relation for mounting of the brackets on vertical or horizontal surfaces.

3. The structure according to claim 1, wherein said tilt cord positioning and retaining means and said ladder tape positioning and retaining means each comprise three substantially parallel bottom bars, each of the two outer bars at their opposed ends having an upwardly projecting end terminating in a tilt rod engaging hook for suspension of the tilt cord and ladder tape positioning and retaining means from the tilt rod.

4. The structure according to claim 3, wherein the middle one of said three substantially parallel bars is provided with a depending lift cord guiding loop.

5. The structure according to claim 3 together with a pair of washers supported on said tilt rod and engaging said hooks, and a ladder tape engaging sleeve frictionally mounted on the tilt rod between said washers, said sleeve and said washers being of substantially the same diameter.
